UNITED STATES PATENT OFFICE.

CHARLES E. POPE, OF SPRINGFIELD, MASSACHUSETTS, ASSIGNOR TO GREAT NORTHERN PAPER COMPANY, OF MILLINOCKET, MAINE, A CORPORATION.

PAPER-MAKING MACHINE.

1,304,903.

Specification of Letters Patent. Patented May 27, 1919.

Application filed August 6, 1917. Serial No. 184,640.

To all whom it may concern:

Be it known that I, CHARLES E. POPE, a citizen of the United States of America, residing at Springfield, in the county of 5 Hampden and State of Massachusetts, have invented certain new and useful Improvements in Paper-Making Machines, of which the following is a specification.

This invention relates to paper machines 10 and more particularly to improvements therein which are adapted for use at the start or after any break in the process of making the paper to facilitate the handling of the web and its transfer from part to 15 part in the machine.

In the initial starting of a web through the machine, or in the starting of a web after any break in the process of making the paper, the web may not be carried at once 20 through the entire machine, but on the contrary may be carried through the machine by stages, as for example, from the wire to the first set of press rolls, from one set of press rolls to another, from the last press 25 rolls to the driers, and so on. Such practice may result, for example, from a subdivision of the machine into numerous sections, each in charge of an operator. Thus one operator may form the ribbon on the 30 wire and see that it is carried to a definite point and another operator will subsequently take the web from the first operator and see that it is carried to another point and so on. Due to the fact that all the sections 35 of the machine may not simultaneously be in readiness to receive the web, it is desirable to permit the web to be started in one section and travel continuously to a given point at which the web may be allowed to travel 40 out of its normal path and accumulate in a mass until the next section is in readiness to receive the web. This invention is concerned with means whereby a web which has been traveling out of its normal path, as 45 by clinging to a roll, for example, may be severed from the accumulated mass and thrown into its normal path.

The invention has for its object to provide in a paper machine in combination with a roll to which the web may cling and travel therewith out of its normal path, a means to sever the web from the misdirected portion and strip it from the roll and cause it to travel along its normal path.

Other objects and advantages of the invention will appear in the following description and in the appended claims.

The invention, in an embodiment at present preferred, is shown for illustrative purposes in the accompanying drawings, in 60 which—

Figure 1 is a diagrammatical view of that part of a paper machine between the last press rolls and the first drying cylinders and shows the invention as applied to 65 the press rolls;

Fig. 2 is a fragmentary side elevational view illustrative of the mounting of the press roll and the improvement associated therewith;

Fig. 3 is a partial cross sectional view of Fig. 2; and

Fig. 4 is a fragmentary perspective view of the improved device shown as removed from the press roll.

Referring to these drawings, a felt 5 carries the web 6 (at first a ribbon) to the last set of press rolls 7 and extends beyond the latter to a guide roll 8, returning over other guide rolls, as indicated in Fig. 1. In line 80 with roll 8 and between it and the first drying cylinder 9 is a guide roll 10, and the fast traveling web is arranged to jump the distance between rolls 8 and 10 and is carried downwardly from the latter into the 85 bight of the first drying cylinder 9 and its associated apron 11 by suitable means (not shown) such, for example, as those disclosed in my prior Patent No. 1,183,113, granted May 16, 1916.

Although the invention will be disclosed in connection with a paper machine of the type mentioned, the invention is capable of use with other types of machines and is independent of the particular machine, the 95 one illustrated and described being chosen merely as an illustrative example of one type with which the invention may be advantageously employed. The invention is also to be disclosed as associated with the 100 press rolls of a paper making machine merely to illustrate one of its specific uses. The invention is, however, capable of other applications than that to be described and may be used to advantage in other parts of 105 a paper machine than that selected for the purposes of illustration.

The upper press roll 7 is generally bare

2 and the web tends to stick and cling to the periphery of the roll and be carried there-around. According to a feature of this invention, the web or more properly, the narrow ribbon, which is customarily formed at the start or after any break in the process of making the paper, is allowed to cling to the upper press roll 7 and to travel therewith until it reaches a doctor 15 mounted to bear upon the roll near the top thereof. The doctor 15 is curved, as shown in Fig. 1, and the ribbon is stripped from the roll by the doctor and allowed to collect in the doctor and on top of roll 7 from which it may be removed from time to time until all is in readiness for the transfer of the ribbon and web to the driers. The curved portion of the doctor prevents the accumulated mass of pulp from falling upon the felt 5 or the ribbon thereon. Slidably mounted, as shown in Fig. 3, is a blade 16 which is manually movable in a direction parallel with the axis of roll 7 by a handle 17. This blade, during the operation above described, is positioned, as shown in Fig. 3, to permit the free passage of the ribbon. Blade 16 has two sharpened edges 18 and 19, arranged substantially at right angles to one another, as clearly shown in Fig. 4, and the former may be manually held against roll 7 by turning handle 17 in the appropriate direction. The blade may obviously be automatically held against roll 7, if desired, but the described construction is preferred.

As soon as everything is in readiness for the ribbon to be transferred to the driers, the operator stationed at the press rolls moves blade 16 inwardly and turns it so that edge 18 bears on the periphery of the roll. As blade 16 is thus moved, the edge 19, cooperating with edge 18, severs the ribbon on the roll, the severing of the ribbon being facilitated by a sliding cutting action, as distinguished from a shearing action. The web, having been severed as described, the blade 16 is held in its inward position and against roll 7 until the ribbon has been stripped therefrom and thrown down upon the felt 5 by the doctor action of the edge 18 and blade 16. The blade may then be retracted to the position shown in Fig. 3. The ribbon is then transferred to the driers as disclosed in my above-mentioned patent or in any other suitable manner.

The axial movement of blade 16, as illustrated, is substantially co-extensive in length with the width of the ribbon customarily formed at the start or after any break in the process of making the paper. It is obvious, however, that this movement of blade 16 may be made co-extensive in length with any width of ribbon or web on the press roll, or other roll to which it may be applied, to act

upon the full width of the web in the manner disclosed.

The invention has been disclosed in one embodiment for illustrative purposes, but the scope of the invention is defined by the appended claims rather than by the foregoing description.

What I claim is—

1. The combination in a paper machine with the upper and lower press rolls thereof, of a scraper blade arranged to be moved into contact with the surface of the upper press roll at a point beyond the pinch of said rolls and below a horizontal plane passing through the axis of the upper press roll, a combined journal and operating rod for said blade, and a bearing supporting said combined member to permit the scraper blade to be moved into contact with or out of engagement with the upper press roll, whereby said blade may be engaged with the latter to strip a lead strip of the wet paper web from the upper press roll and deflect it so that it will move by gravity and its own momentum onto and along with the felt.

2. The combination in a paper machine with the upper and lower press rolls thereof, of a scraper of less length than the rolls arranged to be moved into contact with the surface of the upper press roll at a point beyond the pinch of said rolls and below a horizontal plane passing through the axis of the upper press roll, a combined journal and operating rod for said scraper, a bearing supporting said combined member for axial or rotative movement therein, whereby said scraper may be moved axially or in a rotary manner into contact with or out of engagement with the upper press roll and when in contact therewith may strip a lead strip of the wet paper web from the upper press roll and deflect it so that it will move by gravity and its own momentum onto and along with the felt, and cutting edges for said scraper, substantially as described.

3. In a paper machine, an upper press roll to which the web will cling unless positively stripped therefrom, and a cutting and stripping plate of less length than the roll movably mounted adjacent the upper press roll and directed axially along the surface of the upper press roll at such point as to strip the lead strip of the paper web therefrom, said plate arranged to be moved into contact with said roll to cut said lead strip and arranged to be held against the roll to act as a scraper for the entire width of the lead strip to remove it from said roll and guide it in the desired direction away from said roll and in the path of travel of the web.

CHARLES E. POPE.
